TILE OR SIMILAR ARTICLE

Robert W. Sterrett, Park Ridge, Ill., assignor to Zonolite
Company, Evanston, Ill., a corporation of Montana

Application May 14, 1956, Serial No. 41,485

Term of patent 14 years

(Cl. D18—2)

Fig. 1

Figure 1 is a top plan view of a tile or similar article embodying my new design;

I claim:

The ornamental design for a tile or similar article, substantially as shown.
